UNITED STATES PATENT OFFICE.

JOHN NATHAN, OF LOS ANGELES, CALIFORNIA.

WATER-HEATER.

1,195,601.

Specification of Letters Patent. Patented Aug. 22, 1916.

Application filed January 25, 1915. Serial No. 4,360.

To all whom it may concern:

Be it known that I, JOHN NATHAN, a subject of Great Britain, residing at Los Angeles, in the county of Los Angeles and State of California, have invented a certain new and useful Improvement in Water-Heaters, of which the following is a specification.

My invention relates to a fluid heater, and has especial reference to a device for electrically heating fluids in closed containers, specifically water-bags and the like, objects of this invention being to provide a simple, economical and substantial device, which is adapted to engage the threaded annulus in the neck of a water bag or other container, and form a seal plug therefor and by means of which the water in such container may be heated to any desired temperature. These and other objects are accomplished by the device shown in the accompanying drawing and representing a preferred form.

Figure 1 is a sectional elevation showing the heater as applied to a water bag, the electrodes, the nut for moving one of the electrodes and a means for holding said nut against movement. Fig. 2 is a section on lines 2—2, Fig. 1, showing the nut and the electrode holder movable thereby. Fig. 3 is an edge view of the nut. Fig. 4 is a sectional elevation of a slightly modified form, showing a holder for two electrodes, and the nut for moving the holder, and Fig. 5 is a section on lines 5—5, Fig. 4.

My invention comprises a body portion 1, having a reduced threaded end 2, for engaging a threaded annulus 3, or other threaded portion of a container, as a water bag 4, and forming therefor a seal. In said body are two electrodes 5 and 6, preferably of carbon, the former of which is tightly fitted and stationarily mounted in said body and projects for part of its length beyond the end thereof. The electrode 6 is set in the end of an externally threaded cylindrical member 7, of conducting material, disposed in a vertical bore 8. On and engaging the threads of said member 7, and lying in a slot 9 extending inwardly from the periphery of the body portion, is a nut 10 of conducting material surrounded by a band 11 of insulating material, which projects beyond the periphery of the body 1 to give perch for the thumb or other member for manipulating the nut and causing the vertical movement of the member 7 within the bore 8, and conse-

quently the adjustment of the carbon electrode 6, which is set in said member 7, relatively to the body 1 and the electrode 5 to regulate the temperature desired. Peripheral notches 12, or other temperature indicating means, are provided on said band 11, such notches also serving to receive a lug 13 on a spring plate 14, fixed or otherwise secured to the body, whereby to prevent the accidental turning of the nut 10. The cylindrical member 7 is grooved vertically, as at 15, to receive the end of a screw 16, or other device, for preventing the turning of said member with said nut 10. At its top, the body 1 has a reduced threaded portion 17, for a cap 18, and cavity 19 for purposes to appear presently. On said cap 18 are two current conducting posts 20 and 21, having threaded shanks 22 and 23 extending through the wall of said cap, nuts 24 and 25 on said shanks serving to hold said posts 20 and 21, respectively, in place, and also to fasten between them and washers 26 and 27, the ends of wires 28 and 29, respectively. The wire 28 is run through a vertical hole 30 in said body and is held in tight engagement with the upper end of the fixed electrode 5, by a set screw 31, entering horizontally through said body, and the wire 29 is attached in any convenient manner to the cylindrical member 7. Both wires are coiled upon themselves as at 32 and 33 at points intermediate their attached ends, and these coiled portions, which furnish extra lengths required by the turning of the cap 18 and the movement of the electrode 6, are housed within the space of the cap and the cavity 19. The conducting posts 20 and 21 are arranged to be inserted in a light socket, not shown.

Fig. 4 illustrates a form of my invention wherein the electrodes may be moved simultaneously. Therein the body A is composed of two sections, 34 and 35, screwed together and providing centrally thereof a slot 36, extending inwardly from the periphery, for a nut 37 engaging the threads on a cylindrical member 38, of conducting material disposed in a vertical bore 39, and having a band 40, of non-conducting material projecting beyond the periphery of the body. In the bottom of said cylindrical member 38 is fixed an electrode 41, which extends through and beyond the end of said section 35, and extending through said member 38 is a tube 42 of insulating material having

- an enlarged end for the reception of an electrode 48 of the same length as said electrode 41, and extending through and beyond the end of the section 35. A wire 44 is connected to said electrode 41, extends through a hole 45 in said cylindrical member 38 and is attached at its other end to a binding post 46 in a cap 47 screwed on the section 34 of said body. Another wire 48 is attached to the end of the electrode 43, extends through the tube 42, and is connected at its other end to a binding post 49 in said cap 47. By manipulation of the nut 37, the member 38, and with it the electrodes 41 and 43 are moved relatively to the body A, such movement increasing or decreasing the resistance of the electrodes in the water or other fluid serving as the electrolyte, according to the depth of immersion.
- 20 1. What I claim is:
1. A fluid heater comprising a body of insulating material having a threaded end for engagement with the threads of a container, a cap thereon carrying a plurality of binding posts, a fixed carbon electrode in and extending beyond the end of said body, a movable carbon electrode, and means to move said movable electrode.
  2. A fluid heater comprising a body of insulating material, a plurality of carbon electrodes in said body, means to move one of said electrodes relatively to the other, a plurality of binding posts, and wires connecting said electrodes with said binding posts.
  3. A fluid heater comprising a body of insulating material having a carbon electrode fixed therein, and a carbon electrode movable therein and relatively to said fixed electrode, and means for moving said movable electrode.
  4. A fluid heater comprising a body of insulating material arranged for attachment to a water bag, a cap on said body having a plurality of binding posts, a stationary carbon electrode in said body, a carbon electrode in said body movable relatively to said stationary electrode, a cylindrical member in which said movable electrode is mounted, and means to move said member to adjust said movable electrode relatively to said stationary electrode.
- 10 5. A combined heater and plug for water bags comprising a body of insulating material having a threaded end arranged for engagement with the threads of such bags, a carbon electrode stationarily mounted in and extending beyond the end of said body, a carbon electrode adjustably mounted in said body; means to adjust said adjustable carbon, means to lock said adjusting means against movement; a cap on said body having a plurality of binding posts, and wires connecting said electrodes with said binding posts.
- 15 6. A water heater comprising a body of insulating material, a holder in said body, an electrode carried by said holder and movable beyond the end of said body, an electrode fixed in said body, and means to operate said holder.
- 20 7. A water heater comprising a body of insulating material, an electrode carried thereby and extending beyond the end thereof, a holder in said body, an electrode carried thereby, and a means on said holder and operable from the outside of said body for moving said holder to adjust the electrode carried therein relatively to the electrode carried in said body.
- 25 In testimony whereof I affix my signature in the presence of two witnesses.
- 30 JOHN NATHAN.
